Inventor

Jacob Edson

United States Patent Office.

JACOB EDSON, OF BOSTON, MASSACHUSETTS.

Letters Patent No. 91,832, dated June 29, 1869.

IMPROVED ROCKING AND RECLINING-CHAIR.

The Schedule referred to in these Letters Patent and making part of the same.

To all whom it may concern:

Be it known that I, JACOB EDSON, of 132 Commercial street, Boston, in the county of Suffolk, in the State of Massachusetts, have invented a new and useful Improvement on Rocking and Reclining-Chairs; and I do hereby declare that the following is a full and exact description thereof, reference being had to the accompanying drawings, making a part of this specification, in which—

Figure 1 is a side view, and

Figure 2 is a section over the line A-B, on fig. 1.

To enable others skilled in the art to make and use my invention, I will proceed to describe the construction and operation of the same.

My invention refers to a new mode of making rocking-chairs, so as not to rock direct on the floor or carpet, and thereby lessen the wear and tear of said floor or carpet, but also for the mode of making it into a stationary reclining and easy-chair, when so needed.

a a is a frame, held together by the rods *b b*.

This frame has two corners, *c c*, intended as turning or tipping-points for the rocking.

The support or frame *a a* is connected with the rockers *d d* by means of two bolts, *e e*, that have, in their lower ends, eyes *f f*, playing into slot-holes in the frame *a a*, and affixed to the said frame by means of pins going through the frame and the eyes.

On the upper end of these eye-bolts *e e*, are nuts, *g g*, between which and the rockers *d d*, are spiral springs, *h*, by which means the rocking is facilitated.

The said nuts *g g* may be screwed up or down, so as to adjust the strength of the spring *h*.

Under the rockers *d d*, are fastened elastic coverings, *i i*, made of India rubber, leather, felt, or other suitable material.

The advantages gained by these elastic coverings are, to give a perfect ease to the rocking, and also to make the chair perfectly noiseless when in motion.

The rockers *d d* are also provided with screws, *k k*, one on each side of the bolt *e*, screwing through the rockers, for the purpose of making the rocking-chair into a stationary (or nearly so) easy-chair. As will be seen, when these screws *k k* are screwed down far enough to meet the frame *a a*, the rocking is limited, and the chair may, in this position, be kept nearly stationary, without much rocking to either side.

Having thus described the nature and construction of my invention,

I wish to secure by Letters Patent, and claim—

1. Connecting the rockers *d d* to the frame *a a*, by means of bolts *e e*, springs *h h*, and nuts *g g*, as and for the purpose herein described.

2. In combination with the above, the adjustable screws *k k* and the corners *c c*, for the purpose set forth.

JACOB EDSON.
